UNITED STATES PATENT OFFICE.

LOUIS I. BECKWITH, OF BOSTON, MASSACHUSETTS.

HAMMOCK-SUPPORT.

1,163,637.

Specification of Letters Patent. Patented Dec. 14, 1915.

Application filed August 13, 1914. Serial No. 856,685.

To all whom it may concern:

Be it known that I, LOUIS I. BECKWITH, a citizen of the United States, and resident of Boston, in the county of Suffolk and State 5 of Massachusetts, have invented new and useful Improvements in Hammock-Supports, of which the following is a specification.

This invention relates to folding stands 10 for hammocks, and is designed as an improvement on the stand shown and described in United States Letters Patent No. 1,069,102, granted to me August 5, 1913.

It consists chiefly of a novel and economical 15 form of stand constructed with a minimum of parts, and improved methods of coupling said parts together.

In the accompanying drawings, which 20 illustrate an embodiment of the invention,— Figure 1 is a side elevation, partly in section, of one end of a stand embodying the invention; Fig. 2 is a cross section on the line $x-x$ of Fig. 1, looking to the right; Fig. 3 is a cross section on the line $y-y$ 25 of Fig. 1 looking to the right; and Fig. 4 is an end elevation of the legs when folded together.

The top bar a and four legs b are each 30 constructed of a length of angle iron, and each part is wholly formed out of a single piece of metal. Each leg b is pivotally connected to the top bar a by a brace or link c , which is permanently pivoted at one end to the leg at c' and at the other end at c'' 35 to the shank d of the hook e , which shank is fastened to the top bar a . These links c serve as braces to stiffen the frame when set up in operative position, and as pivotal connections on which the legs and top bar are 40 folded together when the frame is knocked down.

The legs b of angle iron are pivotally connected together near their upper ends at b' . The upper end of each leg b between the 45 pivot hole and the tip, is stamped out to form a lengthwise extending finger f . When the legs b are folded together, the fingers f overlie one another (Fig. 4); when the legs are spread out, the fingers f are crossed and 50 expanded (Fig. 3).

Near each end of the angle iron top bar a is a transverse slot a' , large enough to receive the fingers f when said fingers are folded together, and to allow expansion of 55 said fingers when the legs are spread apart. This slot a' and the fingers f form a lock-

ing device whereby the top bar a and the legs b are securely held together when the frame is set up for use. To assemble the frame the legs are folded together, thereby 60 bringing the fingers f into conjunction. While in this position the fingers f are thrust through the slot a' ; the legs are then swung apart, thereby expanding the fingers f and the legs and top bars are securely fastened 65 together. To knock down the stand, the legs are folded together, the fingers withdrawn from the slot, and the legs then swung back on the links c against the top bar a .

At a suitable distance from the end of the 70 top bar a is a slot a'' through the ridge of the top bar. This slot a'' preferably tapers slightly from its upper end downwardly to a restricted opening at the under side of the angle iron, and forms a mortise to receive one end of a tenon on the shank d .

The hook member e is stamped out of one piece of flat metal, and consists of the hook proper, e , at one end, the flat shank d in the middle, and a tenon or tongue d' at the other 80 end. This tongue d' is fitted to engage the mortise or slot a'' , and when suitably headed over at its end, rigidly and securely fastens the hook member to the top bar a without the use of bolts, nuts, screws, etc. In 85 place of a single tongue d' and single slot a'' , two or more tongues and slots could be used, each tongue separately headed over and secured in its slot. Thus, a single sheet metal punching forms the hook e for the 90 hammock, and the bracket for the brace c , and furnishes its own fastening means.

This simple construction, together with the separable lock, the members of which are merely punched out from the body of the 95 angle iron top bar and angle iron legs, affords a most simple and economical, and at the same time a most efficient hammock frame, containing the fewest possible number of parts, free from castings, screws, 100 bolts, etc., and wholly made of stamped or punched out parts.

While I have shown the two integral fingers f , f , as overlying each other when the legs are in closed position, as my preferred 105 form, it will be understood that I do not intend to limit my invention to that specific construction, but that any relative arrangement of said fingers, whether superposed or not, such that they will be in position to pass 110 through their recesses in the top bar when the legs are closed together and will move

into locking position when the legs are spread apart, is within the contemplation of the claims.

I claim:

1. A folding frame comprising a top bar formed with a slot near each end, and a pair of pivoted supporting legs, the end of each leg being stamped out to form a finger integral with the body of the leg, said fingers being adapted to engage said slot and form a locking device to secure the legs to the top bar when said legs are unfolded.

2. A folding frame comprising a top bar of angle metal formed with a slot near each end, and a pair of pivoted supporting legs of angle metal, the end of each leg being stamped out to form a finger integral with the body of the leg, said fingers being adapted to engage said slot and form a locking device to secure the legs to the top bar when said legs are unfolded.

3. In a folding frame comprising a top bar of angle metal and a pair of legs, a hook

member formed of a single flat plate, having a tenon extending through a slot provided therefor in the apex of the top bar and headed over rigidly to secure the hook member to the top bar, a shank portion, and an integral hook, and links pivotally connecting said shank portion of the hook member and said legs.

4. In a folding frame comprising a top bar and a pair of legs, a hook member formed of a single piece of metal having a tenon extending through a slot provided therefor in the top bar rigidly to secure the hook member to the top bar, a shank portion and an integral hook, and links pivotally connecting said shank portion of the hook member and said legs.

Signed by me at Boston, Massachusetts, this tenth day of August, 1914.

LOUIS I. BECKWITH.
